UNITED STATES PATENT OFFICE

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT

COMPENSATING MECHANISM

Application filed May 23, 1927. Serial No. 193,650.

This invention relates to compensating mechanism, particularly as applied to heading or upsetting machines, although not limited thereto. It is the object of the invention, among other things to provide a simple and effective device of this character which will insure the full stroke of the punch slide at the variable limits of its stroke without adjustment of the parts from which it derives its power, and further, to provide in its structure a certain definite part that will break, if the punch slide, for any reason is held in a locked position, when under normal conditions it should be free to move. 10 With these, and other objects in view, as will more fully appear, the invention consists of certain features of novel construction, and arrangement of parts as described and illustrated in the accompanying drawings, and particularly pointed out in the claims, it being understood, however, that within the scope of what is claimed, changes in form, proportion, size and details of construction may be made without departing 20 from the spirit or modifying any of the advantages of the invention.

Referring to the drawings in which like numerals designate like parts in the several figures.

30 Figure 1 is a side elevation of a portion of a header or upsetting machine with my new and improved mechanism associated therewith;

35 Figure 2 is a fragmentary transverse sectional view thereof, taken generally upon line 2—2 of Figure 1.

A heading, upsetting machine or the like is provided with a gate 10, which reciprocates within a body member 11 and movable vertically thereon is a punch slide 12, carrying a punch block 13, in which are fixed one or more punches 14.

40 The limit of movement of this punch slide relatively to the gate is determined by stop mechanism, consisting usually of a rod 15 secured in a fixed part and having nuts 16 thereon and a stop screw 17 held against accidental movement by a lock nut 18.

45 The lower end of the stop screw 17 contacts with a part 19 or the like and thus limits

the down position of the punch slide, and the position of the nuts 16 on the rod 15 determines the limits of the up position of the punch slide, these positions being variable through the adjustment of the nuts 16 and 55 stop screw 17.

Various ways are provided for locking the punch slide against movement, when each of the punches is in an operative upsetting position, such means being common and well known in the art. A portion of one of such means is shown herein and comprises a locking stud 49 having angular faces upon opposite sides of the head thereof and fixed in the punch slide, and a movable locking bolt 60 50 also having angular faces upon opposite sides of its outer end. This locking bolt actuated by mechanisms (not shown) toward and away from the punch slide rides either on the top of or in underneath the locking stud 49 65 thus locking the punch slide either against the stop screw 17 or the nuts 16 in its down or up positions respectively.

Movement of the punch slide 12 relatively to the gate 10 is derived from the rock shaft 75 20 journaled in the body member 11 or other part and having an operative connection with the foot plate 21 connected with the slide and the cradle 22.

The mechanism above described is old in 80 the art and with the exception of the operative connection between the rock shaft and punch slide, constitutes no part of my present invention.

In the operation of a header or the like, it 85 is necessary, upon occasion, to vary the limits of the stroke of the punch slide upon the gate. These limits are determined, as above described, by the position of the nuts 16 and stop screw 17.

90 My invention relates particularly to the mechanism located between the source of power (rock shaft) and the punch slide for imparting relative movement to the punch slide on the gate, whereby, irrespective of the length or position of the stroke of the punch slide, the mechanism will operate and adjust itself automatically to such differences in stroke; and further, if perchance the punch slide should be in any one of its locked posi- 95 100

tions, and thus held against movement, my improved mechanism will either accommodate itself to these new conditions, or a readily replaceable part will break without causing injury or damage to other more costly and not so readily replaceable parts.

In the drawings, 23 designates the shaft journaled in the body member of the machine or other parts, having thereon a journal block 24, which is slidable between the walls of the slot 25 in the connection arm 26. This arm derives lengthwise movement from a cam 27 on the rock shaft 23, through a roll 28 journaled on the stud 29 fixed in said arm. Fixed on the rock shaft 20 is an arm 30 having therein stop screws 31 which are locked in their adjusted positions by the nuts 32. Journaled on the rock shaft 20, adjacent to the arm 30, is the rock member 33 having a radial slot 34 therein, and provided at one end with a head 35, and at the other end with a base portion 36, having the pockets 37 and lugs 38, through the latter of which are the screws 39.

Projecting through the slot 34 is a stud 40, upon which is journaled the bushing 41 fixed in the yoke end 42 of the connection arm 26, with nuts 43 and 44 upon opposite ends thereof. The position of this stud 40 toward and away from the rock shaft 20 is determined by the sleeve 45 threaded into the rock member 33 with its inner end impinging against the stud 40 and the lock screw 46 rotatable therein and threaded into the stud 40. By manipulation of the sleeve 45 and lock screw 46 the stud 40 can not only be moved toward and away from the rock shaft but can be securely locked in any of such adjusted positions. Upon opposite sides of the center of the rock shaft 20 are the two pairs of flat flexible plates 47, the lower end of each pair projecting into one of the pockets 37. The screws 31 contact with the inner of these plates 47, near the outer end, and near the lower end thereof the screws 39 contact with the outer of these plates. Varying tensions of the plates 47 are derived from the screws 39. When the mechanism is in its normal position the tension of the plates 47 is against the head 35 and there is a slight clearance between the screws 31 and the inner of the two plates 47 so that one set of the plates is not counteracting the opposite set. While I have illustrated these plates as being arranged in pairs, a single plate, or more than two in each set, may be substituted for those shown. Lateral movement of the plates relatively to the rock member 33 is prevented by the lugs 48 on the head 35.

In operation, motion is transmitted to the rock shaft 20 from the shaft 23 through the connection arm 26, which imparts a rocking movement to the member 33 and through the plates 47 to the arm 30.

The position of the stud 40 is such as to

impart approximately such a rocking movement to the rock member 33 as will give the requisite reciprocatory movement to the punch slide 12 on the gate 10. This adjustment, however, is only approximate and if there is still motion left in the connection arm 26 after either one of the extreme movements of the slide 12 has been reached, then such excess movement is absorbed by the yielding plates 47, the plates upon one side of the rock member 33 yielding at the limit of one movement of the stroke of the punch slide and the plates upon the opposite side yielding at the opposite limit.

If any of the mechanism that imparts reciprocal movement to the gate should break or become disarranged in its parts, such contingency and others, may prevent the disengagement of the punch slide locking mechanism. Thus, the punch slide will be held against relative movement in the gate. In such case, the mechanism for reciprocating the slide relatively would ordinarily break. With my device, however, in such contingency, the flexible plates 47 will be called upon to yield considerably more than normally and perhaps sufficiently to permit the operation of the connection arm 26 without imparting movement to the punch slide 12. If, however, the plates should not yield sufficiently for this purpose, one set would break, thus permitting the operation of the connection arm 26 and associated parts without imparting movement to the slide 12.

The plates 47 are comparatively inexpensive and replacement of one or more thereof, if broken, will restore the mechanism to its normal condition with the minimum expenditure of time and labor.

What I claim as new is:—

1. In a mechanism of the character described, a shaft, an arm on said shaft, a rock member journaled on the shaft having a head formed with recessed lugs upon each side thereof and a foot having pockets therein, a yielding member on each side of said rock member having an end received in one of said pockets and having its opposite end slidably projecting through one of the recessed lugs and engaging said arm, and means for actuating said rock member.

2. In a mechanism of the character described, a shaft, a radially projecting arm carried by said shaft, a rock member journaled on said shaft adjacent the arm, said rock member having a foot formed with a pair of spaced pockets, and a head formed with a pair of spaced openings, a pair of spring members, each of said spring members having an end received in one of said pockets and having its opposite end projecting through and beyond an opening in the head and engaging said arm, and means for actuating the rock member.

3. In an operating mechanism for punch

slides, a shaft, an arm on said shaft, a rock member journaled on the shaft having a head and a foot, a yielding member on each side of said rock member having an end engaged with the arm and adapted to break upon jamming of the punch slide or locking thereof against movement, means carried by the head for slidably engaging each member between the ends of the latter, means to adjustably connect each member to the foot, and means to actuate said rock member.

4. In an operating mechanism for punch slides, a shaft, an arm on said shaft, a rock member journaled on the shaft and having a head and a foot disposed on opposite sides of the shaft, resilient means on each side of the rock member said resilient means being adapted to break upon jamming of the punch slide or locking thereof against movement, adjustable means carried by the arm on each side thereof and engaged with the adjacent ends of the resilient means, means to guide the resilient means from the head, means to adjustably connect the resilient means to the foot, and means for actuating said rock member.

In testimony whereof, I have hereunto affixed my signature.

RICHARD LESTER WILCOX.
